UNITED STATES PATENT OFFICE.

JAMES BATSON ROSS, OF TORONTO, ASSIGNOR OF ONE-HALF TO H. T. WATKINS, OF ST. BERNICE, INDIANA.

CONVERTIBLE CHAIR.

SPECIFICATION forming part of Letters Patent No. 333,892, dated January 5, 1886.

Application filed October 3, 1885. Serial No. 178,956. (No model.)

To all whom it may concern:

Be it known that I, JAMES B. ROSS, a citizen of the United States, and a resident of Toronto, in the county of Vermilion and State of Indiana, have invented certain new and useful Improvements in Combined Chair, Ironing-Stand, &c.; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view showing my improved convertible chair, ironing-stand, and clothes-rack folded and in position to be used as a chair. Fig. 2 is a perspective view showing the device extended and in position to be used as an ironing-stand and clothes-horse. Fig. 3 is a longitudinal vertical sectional view showing the device extended as in Fig. 2. Fig. 4 is a rear view showing the device folded as in Fig. 1, and Fig. 5 is a vertical transverse sectional view taken on the line *xx* in Fig. 2.

The same letters refer to the same parts in all the figures.

This invention relates to an improved article of combination-furniture, comprising a chair, ironing-stand, clothes-rack, and a folding leaf, which may serve as a writing-desk; and it has for its object to provide an article of this class which shall possess superior advantages in point of simplicity, durability, and general efficiency.

With these ends in view it consists in the improved construction, arrangement, and combination of parts, which will be herein-after fully described, and particularly pointed out in the claims.

In the drawings hereto annexed, A designates the chair-frame, the front and rear legs of which (designated, respectively, by letters B and C) are made preferably of bent wood, as will be clearly seen in the drawings hereto annexed, so as to form also the arms or arm-rests D.

E is the seat, which is of ordinary construction. Pivoted in longitudinal slots F F in the said seat, near its sides or outer edges, are a

pair of upwardly-extending arms, G G, extending through slots H in the arm-rests, and having their upper ends connected pivotally centrally with the sides of the back-frame, I. The latter is provided with a pair of semicircular or segmental brackets, J J, having perforations K K, adapted to register with perforations L L in the arms G. Suitably attached to the arm-rests are a pair of spring bolts or latches, M M, which may be made to enter or engage the perforations in the arms and brackets, thereby serving to retain the back-frame in any one of the several positions to which it may be adjusted. The sides of the back-frame are connected by cross-pieces N N, the upper one of which is connected with the central one by the back-rest O. Hinged to the outer edges of the back-frame, and arranged to fold upon its rear side, are a series of bars, P P, having inwardly-extending arms Q Q, which, when extended, as shown in Fig. 2 of the drawings, serve as racks upon which clothes may be hung for drying or airing. Suitably hinged to the lowermost cross-piece of the back-frame is the ironing-board R, to the under side of which, near its outer end, is hinged a supporting-bar, S, forming a leg for supporting the outer end of the ironing-board, when the latter is in use. When the ironing-board is not in use, it may be folded up against the back-frame, as will be seen in Figs. 1 and 4 of the drawings, thus serving to confine the clothes-racks in their folded position. When thus folded, the ironing-board may be confined and retained by means of a turn-button, T, at the upper end of the back-frame. Suitably hinged to the back-frame at or near its lower end is a brace rod or bar, U, the free end of which may engage a staple, V, upon the rear edge of the seat, thereby assisting to retain the back-frame in its elevated or raised position when the clothes-racks and ironing-board are in use. This brace-bar, when not in use, will fold up against the inner side of the back-frame, as shown in Fig. 1 of the drawings. Suitably hinged to one of the arm-rests of the chair is a folding leaf, W, that forms a convenient reading and writing desk. When extended for use, this leaf may be supported by means of a brace-rod, which may be constructed

and arranged in any suitable well-known manner.

From the foregoing description, taken in connection with the drawings hereto annexed, 5 the operation and advantages of this invention will be readily understood without requiring any extended explanation.

The general construction is simple and inexpensive, and the device is capable of being 10 easily and quickly converted to its various uses. When the use of the ironing-board and clothes-racks is not required, the device forms a neat and comfortable arm-chair, and, as such, occupies no unnecessary space. The 15 cost of manufacture is moderate, and it forms a neat and convenient article of furniture.

Having thus described my invention, I claim and desire to secure by Letters Patent of the United States—

20 1. The combination of the chair-frame having slotted arm-rests, the upwardly-extending arms pivoted in longitudinal slots near the edges of the seat, the back-frame connected pivotally to the upper ends of the said arms, 25 and the curved or segmental brackets secured to the said back-frame and having perforations adapted to register with perforations in the supporting-arms, and suitable spring bolts

or latches secured to the arm-rests and adapted to engage the said perforations for the purpose of retaining the back-frame in any position to which it may be adjusted, substantially as and for the purpose herein set forth. 30

2. In a combined chair, ironing-board, &c., the combination of a chair-frame, the back-frame connected with the chair-seat by means of pivoted supporting-arms, an ironing-stand hinged to the lower edge of the back-frame, a supporting-leg hinged to the under side of the outer end of said ironing-stand, a brace 40 between said leg and stand, folding clothes racks or frames hinged to the sides of the said back-frame, and a turn-button at the upper edge of the latter, adapted to secure the ironing-stand when the latter has been folded over 45 the folding clothes-racks, which may thereby be secured in their folded position, all arranged and operating substantially as and for the purpose herein shown and specified.

In testimony that I claim the foregoing as my own I have hereunto affixed my signature in presence of two witnesses.

JAMES BATSON ROSS.
